UNITED STATES PATENT OFFICE.

NICHOLAS LOESL, OF RICHMOND HILL, NEW YORK, ASSIGNOR TO AMERICAN CAN COMPANY, OF NEW YORK, N. Y., A CORPORATION OF NEW JERSEY.

SIFTER-TOP-CLOSING DEVICE.

Application filed May 28, 1925. Serial No. 33,581.

My invention relates to automatic feeding mechanism for box tops or the like and has particular application to the feeding of talcum powder box tops in which a cap is rotatably positioned upon a neck projecting from the breast of the top.

An important object of the invention is the provision, in association with the feeding mechanism, of means for closing sifter openings, such as those provided in the top and rotatable cap of talcum powder cans. Heretofore, talcum powder can tops have been shipped from the can factory without ascertaining whether or not all of the caps have been turned to close the sifter openings and the result has been that the manufacturer of the powder has had to test each one of said tops to see whether or not they were closed, and, if they were not, to close them. This has entailed an additional operation which, in the handling of thousands of cans by hand, has proved to be tedious and expensive. As indicated above, the present invention contemplates the provision of automatic means for performing this operation at the can factory in connection with another necessary operation, namely the feeding operation involved in the automatic manufacturing and handling of said tops and thereby eliminates the additional labor and expense heretofore required of the manufacturer who uses the cans.

Another object of the invention is the provision, in mechanism of this character, of means for preventing damage to the tops in the event that they are not properly positioned with respect to the operation of the feeding devices, thereby rendering it unnecessary to operate said devices in timed relationship.

Numerous other objects and advantages of the invention will be apparent as it is better understood from the following description, which, taken in connection with the accompanying drawings, discloses a preferred embodiment thereof.

Referring to the drawings,

Figure 1 is a top plan view of an apparatus in which my invention is embodied; Fig. 2 is a side elevation thereof, partially broken away for convenience in illustration;

Fig. 3 is a view similar to Fig. 1, with the parts in different position; and

Fig. 4 is a view partially in section and partially in elevation of a part of the appa-

ratus looking toward the right in Figs. 1 and 3 and showing the means for operating the transverse feeding mechanism and cap closing device.

On said drawings, illustrating the best manner in which I have thus far contemplated applying the principles of my invention, the reference character 11 indicates a conveyor belt, adapted to carry can tops 12, received from a die press or other apparatus, said belt being directed over suitable rollers, one of which is shown in the drawings and indicated by the reference character 13. Said roller is carried upon a shaft 14, journaled in bearings 14' provided in the upper ends of lugs 15 arising from a base member 16, held in place by means of bolts 17, or in any preferred manner. Obviously, the roller at the opposite end of the conveyor may be supported in the same or any preferred manner and may be driven by well-known means from any available source of power. Arranged transversely of said conveyor 11, a short distance from the right-hand end thereof, viewing Figs. 1 to 3 of the drawings, is a transverse feeding mechanism adapted to remove the tops from said conveyor and direct them into a passageway 18 for delivery to a suitable receptacle for the finished tops. Said passageway 18 is provided with side walls 19 and 20 and a wall 21, of a transverse guideway 22, is arranged in line with said wall 20 and is adapted to stop the tops when they are advanced by said belt conveyor to position from which they may be moved directly into said passageway 18. It should be understood that a chain can be substituted for the belt 11 and the same results accomplished.

Said transverse feeding mechanism comprises a block 23 carried upon a slide 24, which is formed with a depending lug 25, to which a bar 26 is pivotally secured at 27, the opposite end of said bar being pivoted at 28 to one arm 29 of a bell-crank 31, pivoted at 32 to the floor, or other fixed support 33. Said slide 24 is supported in a frame 34, fixed in place by bolts 35, said frame also supporting the passageway 18 and a bed part 36 over which the conveyor 11 travels, said bed part being provided with side walls 37 and 38 between which the tops 12 are confined.

The other arm 39 of the bell-crank 31 is pivotally connected at 41 with a vertically

disposed pitman 42, the upper end of which is bifurcated, as indicated at 43, and secured at 44 to a slide 45 disposed in a guideway formed in a frame part 46, the upper end of 5 said slide carrying a roller 47 adapted to follow a cam 48 secured to a shaft 49 forming a part of the operating mechanism of the apparatus. Said roller 47 is held in contact with the cam by means of a spring 10 51, secured at its upper end to the bifurcated end 43 of the pitman 42 and at its opposite end to the side wall 19 of the passageway 18. Said spring also provides a yielding driving connection for the feed block 23, so 15 that in the event a top 12 is not properly positioned when said block advances, the latter may yield and thus avoid damage to said top, which will be advanced by the conveyor 11 to proper position when said block 20 is next retracted.

The forward end of said block is provided with a flange 52 adapted to be disposed above the top 12 during the advancing movement. A beveled hook 53 is provided at the 25 entrance of the passageway 18 to prevent retracting movement of the tops after they have been advanced into said passageway, said hook being normally held in inward position by means of a coil spring 54, mounted 30 upon a pin 55 arising from a boss 56 projecting from the wall 19, one end 57 of said spring being in contact with the outer side of said wall 19 and the other end 58 thereof with the side of the shank of the 35 hook 53, which is also pivoted on said pin 55.

A closing member 59 is pivoted at 61 to the top of the feed block 23, near the forward end and slightly to one side of the longitudinal center thereof. A laterally extending arm 62 of said closing member is 40 pivoted at 63 to a friction drag block 64 disposed in the guideway 22, the outer wall of which is formed by a side bar 65 secured in place by means of screws 66. A forwardly extending finger 67 on said member 59 is adapted to be moved toward the right, viewing Figs. 1 and 3, by reason of the friction upon the drag block 64 when the feed block 23 is advanced. This disposes said 45 finger at one side of a scalloped sifter cap 68, rotatably positioned upon the neck of the tops 12. This position of said closing member is shown in Fig. 1. After said feed block 23 has reached the end of its forward stroke and the box top is positioned in the 50 passageway 18, in which it is held by the hook 53, said feed block is retracted and the friction upon the drag block 64 thereupon tends to move the closing finger 67 inwardly 55 into contact with the cap 68, as shown in Fig. 3. As hereinabove stated, said cap may be, and often is, arranged with the sifter openings unclosed and said finger 67 serves to rotate said cap upon the backward stroke 60 of said feed block, in manner which will be 65 obvious from inspection of Fig. 3. The forward end of said finger engages within one of the scallops of the cap and if the latter is not in closed position, it will be positively turned by said finger, thereby insuring 70 that the sifter openings in all of the tops will be closed. In the event that said cap should be already closed, it will be understood that said finger slides off the cap, since there is less friction in this action than the 75 friction upon the slide block 64. In order to limit the backward movement of said feed block 23 and to insure the proper withdrawal of the finger 67, I provide a stop pin 69, adapted to be engaged by a third extension 80 or arm 71 on said member 59, said member being thereby arranged in the position shown in Fig. 1 and the device being then ready for the next forward stroke. Inasmuch as the closing operation just described 85 is performed as an incident to the already necessary feeding operation, the additional expense is relatively small and the manufacturer may be sure that the tops which he ships to his customers all have their sifter 90 caps closed and are ready for positioning upon a filled container without requiring from the customer the labor and expense heretofore necessary in testing each top.

It is thought that the invention and many 95 of its attendant advantages will be understood from the foregoing description, and it will be apparent that various changes may be made in the form, construction and arrangement of the parts without departing 100 from the spirit and scope of the invention, or sacrificing all of its material advantages, the form hereinbefore described being merely a preferred embodiment thereof.

I claim:

1. In combination, feeding mechanism for box parts, said box parts including a rotatably positioned cap having sifter openings therein, and means automatically operable during the operation of said feeding mechanism for turning said caps upon the box parts to close said sifter openings, said means comprising a closing member bearing against the side of said cap, and devices for reciprocating said closing member. 110

2. In combination, a conveyor for box parts, a reciprocating member operating transversely of said conveyor to remove said box parts therefrom, and means associated with said reciprocating member for automatically moving cover members on said box parts to close sifter openings formed therein. 120

3. In combination, a feeding device for box parts, and a closing member reciprocated by movement of said feeding device for closing cover members on said box parts. 125

4. In combination, a feeding device for box parts, a closing member reciprocated by movement of said feeding device for clos- 130

- ing cover members on said box parts, and means providing a yielding driving connection for said feeding device. 65
5. In combination, a conveyor for box parts, a feeding device operating transversely of said conveyor for removing the box parts therefrom, and means associated with said feeding device for closing cover members on said box parts. 70
10. 6. In combination, a conveyor for box parts, a feeding device operating transversely of said conveyor for removing the box parts therefrom, means associated with said feeding device for closing cover members 75
- 15 on said box parts, a support for receiving the box parts as they are removed from said conveyor, and means for preventing return movement of said box parts during operation 80
- of said closing means.
20. 7. In combination, a conveyor for box parts, a feeding device operating transversely of said conveyor for removing the box parts therefrom, means associated with said feeding device for closing cover members 85
- 25 on said box parts, a support for receiving the box parts as they are removed from said conveyor, means for preventing return movement of said box parts during operation of 90
- said closing means, and means for restoring said closing device to initial position.
8. In combination, a conveyor for box parts, a feeding device operating transversely of said conveyor for removing the box parts therefrom, and means associated with said feeding device for closing cover members 95
- 15 on said box parts, said feeding device including a sliding feed block and said closing means comprising a member pivoted to said block and having a finger engageable 100
- 40 with the cover member for closing the same and a friction guideway and drag block for operating said member.
9. In combination, a conveyor for box parts, a feeding device operating transversely of said conveyor for removing the box parts therefrom, and means associated with said feeding device for closing cover members 105
- 45 on said box parts, said feeding device comprising a reciprocating mechanism and 110
- 50 said closing means comprising an element pivotally associated with said mechanism and having a part movable into engagement with said cover member for closing the same and a friction drag member for operating said element. 115
10. The combination of a cap-turning member, feeding means for carrying a can-part and a closure rotatable thereon near to said cap-turning member whereby the latter turns the cap on said can-part, and a passage-way along which the can parts are caused to progress, said passage-way having means for holding the can-part from turn- 120
- ing during the operation of said cap-turning member. 65
11. In combination, feeding mechanism for actuating container parts, said container parts including a rotatably positioned cap having sifter openings therein, and mechanism movable sidewise relative to the axis of the container part and cap for turning said caps upon the container parts to close said sifter openings. 70
12. In combination, reciprocating feeding mechanism for container parts, said container parts including a rotatable closure member, and means relative to which the said parts are carried by said feeding mechanism, for engaging and turning said closure member upon movement in one direction of said 80
- reciprocating feed. 75
13. In combination, reciprocating feeding mechanism for container parts, said container parts including a rotatable closure member, means for engaging and turning said 85
- closure member upon movement in one direction of said reciprocating feed, and means for preventing return movement of said container parts during operation of said closing means. 90
14. In combination, reciprocating feeding mechanism for container parts, said container parts including a rotatable closure member, means for engaging and turning said closure member upon movement in one 95
- direction of said reciprocating feed, and means for holding said container parts during operation of said closing means. 100
15. In combination, reciprocating feeding mechanism for container parts, means for engaging and turning cover members on said container parts upon movement in one direction of said reciprocating feed. 105
16. In combination, reciprocating feeding mechanism for container parts, means for engaging and turning cover members on said container parts upon movement in one direction of said reciprocating feed, and means providing a yielding driving connection for 110
- said feeding mechanism. 110
17. In combination, reciprocating feeding mechanism for container parts, means for engaging and turning cover members on said container parts upon the return stroke of said reciprocating feed. 115
18. In combination a feeding mechanism for container parts, said container parts including a rotatable closure member, a finger for frictionally engaging said closure member on one of its sides and turning it, and means whereby the container parts and finger are caused to have relative sidewise movement for the turning of the closure member. 120
